UNITED STATES PATENT OFFICE

RUDOLPH EBERHARDT, OF BROOKLYN, NEW YORK

DESIGN FOR A TOILET-ACCESSORIES CONTAINER

Application filed July 14, 1930. Serial No. 36,351. Term of patent 7 years.

To all whom it may concern:

Be it known that I, RUDOLPH EBERHARDT, a citizen of the United States, residing at Brooklyn, county of Kings, city of New York, and State of New York, have invented a new, original, and ornamental Design for a Toilet-Accessories Container, of which the following is a specification, reference being had to the accompanying drawing, forming a part thereof.

The novelty of the design resides in the particular type of ornamentation shown on the sides of the container.

The figure is a plan perspective view of a toilet accessories container, showing my new design.

I claim:—

The ornamental design for a toilet accessories container, as shown and described.

RUDOLPH EBERHARDT.
